(57) **CLAIM**

The ornamental design for a cigarette package, as shown and described.

DESCRIPTION

FIG. 1 is a perspective view of a first embodiment of the cigarette package showing the design of the disclosed invention;

FIG. 2 is a front view thereof;

FIG. 3 is a back view thereof;

FIG. 4 is a side view thereof;

FIG. 5 is a side view thereof;

FIG. 6 is a top view thereof;

FIG. 7 is a bottom view thereof;

FIG. 8 shows a blank of the first embodiment of the cigarette package shown in FIGS. 1-7;

FIG. 9 is a perspective view of a second embodiment of the cigarette package showing the design of the disclosed invention;

FIG. 10 is a front view thereof;

FIG. 11 is a back view thereof;

FIG. 12 is a side view thereof;

FIG. 13 is a side view thereof;

FIG. 14 is a top view thereof;

FIG. 15 is a bottom view thereof;

FIG. 16 shows a blank of the second embodiment of the cigarette package shown in FIGS. 9-15;

FIG. 17 is a perspective view of a third embodiment of the cigarette package showing the design of the disclosed invention;

FIG. 18 is a front view thereof;

FIG. 19 is a back view thereof;

FIG. 20 is a side view thereof;

FIG. 21 is a side view thereof;

FIG. 22 is a top view thereof;

FIG. 23 is a bottom view thereof; and,

FIG. 24 shows a blank of the third embodiment of the cigarette package shown in FIGS. 17-23.

The broken lines represent environmental subject matter that forms no part of the claimed design.
